UNITED STATES PATENT OFFICE

GEORGE C. CLARK, OF INDIANAPOLIS, INDIANA
IDENTIFICATION CARD AND LICENSE HOLDER

Application filed December 16, 1929. Serial No. 414,463.

This invention relates to devices for use by operators of vehicles to carry their license and identification cards in a convenient place within the automobile or vehicle.

5 The primary object of this invention is to provide a receptacle for operator's license and identification card, the container being in the nature of a drawer slidably mounted on a stationary part of the vehicle preferably interior 10 of the vehicle and upon the dash board of the vehicle, whereby access may be conveniently had thereto when necessary for display either or both the operator's license or identification card.

15 A still further object of the invention is to provide a container of this character which is simple in construction, consists of but few parts, can be readily secured to the dash board of the vehicle without marring the construction of the dash board or in any way detracting from the appearance of the dash board.

20 Other objects and advantages of the invention will be apparent during a study of the following description, taken in connection with the accompanying drawings wherein:—

25 Figure 1 is a fragmentary end elevational view of a dash board looking at the front of the dash board, the same being equipped with my improved license and identification card holder.

Figure 2 is a fragmentary detail sectional view taken therethrough substantially on the line 2—2 of Figure 1.

30 Figure 3 is a bottom plan view of the receptacle or drawer.

Figure 4 is a perspective view of the guide plate for the drawer.

35 Figure 5 is a perspective view of the drawer.

Figure 6 is a detail elevational view showing the drawer in open position and having an operator's license arranged therein.

40 With reference more in detail to the drawings, it will be seen that I have designated generally by the reference character D a dash board of a motor vehicle such as an automobile, the dash board being shown fragmentarily.

45 In the present embodiment of the inven-

tion, the receptacle is in the nature of an elongated shallow drawer 5, the drawer 5 being of suitable length and width to accommodate an operator's license card or identification card or both, if desirable. For slidably supporting the drawer to the dash board D, I provide an attaching bracket designated generally by the reference character B. This attaching bracket is in the nature of an elongated rectangular plate 6 adapted to be secured to the bottom wall d of the dash board to extend transversely of the bottom wall inwardly from one end of the dash board. The plate 6 adjacent one end thereof and inwardly from the longitudinal side edges thereof is provided with elongated slots 7, and bolts 8 are extended through the slots and suitable openings 9 in the bottom wall d of the dash board registering with the slots. Wing nuts 10 are threadedly engaged with these attaching bolts for securing the plate in any predetermined adjusted position to the said bottom wall of the dash board.

46 The plate 6 at its opposite longitudinal edges thereof is provided with longitudinally extending depending guide flanges 11, and the free edges of these guide flanges 11 are turned toward one another as at 12 to provide internal guide channels 13 for slidably accommodating the longitudinal side of the drawer 5 as shown to advantage in Figures 1 and 6.

47 The plate 6 at the rear end thereof or that end remote from the slots 7 is provided with a downwardly depending stop flange 14 against which the rear end wall of the drawer 5 is adapted to abut when said drawer is slid inwardly to a closed position. Such is clearly suggested in Figure 2.

52 To facilitate sliding movement of the drawer 5 either to a closed or opened position, the said drawer 5 at the forward end thereof has its bottom wall provided with a depression 15 to provide on the under surface of the drawer at the forward end thereof what may be termed a finger engaging lug 16.

57 In many States, and especially in the State of Indiana, there is now what is known as a driver's license law under which it is compulsory for the operator of a vehicle such as a

motor vehicle, that is, an automobile or the like to carry his or her license either on his or her person or within the car at all times during the operation of the vehicle.

- 5 Manifestly, a vehicle equipped with a sliding drawer such as suggested by this invention, will be well provided with means whereby the operator may have at hand at all times within the vehicle his license card or identification card, and the license card or identification card or both being carried in the drawer in this manner mutilation of the card and the wear and tear to which such cards are subjected to when being carried about on 10 one's person or in one's pocket will be eliminated.

It will also be noted, that if desired the drawer may be normally in a closed position. However, if it be desirable of having the 20 drawer partially open so that the contents thereof may be readily discernible, the guide channels 13 will provide suitable supports for the drawer in its partially opened position.

From the foregoing it will be also noted 25 that I have provided a neat and attractive drawer or receptacle for this purpose which when secured to the dash board or any other stationary part of the vehicle within convenient reach of the operator or any other interested person will not in any way detract 30 from the appearance of the vehicle, and, of course, it is to be understood that the drawer and attaching plate therefor may be formed of polished metal or any other suitable material 35 suitably painted or finished as to conform in color with that part of the vehicle to which it may be attached.

Even though I have herein shown and described the preferred embodiment of my invention, it is to be understood that the same is 40 susceptible to changes fully comprehended by the spirit of the invention as herein described, and the scope of the appended claims.

Having thus described my invention, what 45 I claim as new is:

1. In an operator's license card and identification card receptacle of the character described, an attaching plate, means for adjustably securing said attaching plate to a stationary part of a vehicle, said plate being provided on opposite longitudinal side edges thereof with longitudinally extending guide channels, said plate at one end thereof and extending transversely thereof being provided with a downwardly directed stop flange, a drawer slidably supported in said channels for sliding movement in a plane parallel to said plate, and the bottom wall of said drawer at the forward end thereof 50 having a depression formed therein to provide exteriorly of the drawer a finger engaging lug to facilitate sliding movement of said drawer.

2. In combination, a dash board, a plate 55 adjustably mounted on said dash board,

means for adjustably mounting said plate, a pair of guide channels on said plate, a drawer having its opposite sides slidable in said guide channels, said drawer having the bottom thereof provided with a depression to 70 provide exteriorly of the drawer a finger engaging lug.

In testimony whereof I affix my signature.
GEORGE C. CLARK.
